UNITED STATES PATENT OFFICE.

RUFUS CARTER WILLIAMS, OF RICHMOND, VIRGINIA.

MEANS FOR ENTERING ACCOUNTS.

SPECIFICATION forming part of Letters Patent No. 783,738, dated February 28, 1905.

Application filed June 22, 1904. Serial No. 213,639.

To all whom it may concern:

Be it known that I, RUFUS CARTER WILLIAMS, residing at Richmond, in the county of Henrico and State of Virginia, have invented 5
a new and Improved Means for Entering Accounts, of which the following is a specification.

This invention seeks to provide a means for entering accounts of a simple and convenient 10 form so arranged and combined that a single entry on a statement-sheet will be duplicated on a journal or ledger sheet and also on a bill-sheet. The several forms that constitute my 15 complete means for entering accounts have such correlation that the duplicate statement and journal or ledger sheet can be readily separated from the block of way or bill sheets, and a plurality of duplicate journal or ledger sheets can be used in connection with a single 20 set or block of way or bill sheets in such a manner that the way or bill sheet entries made against the same purchaser at different times can be conveniently carried on the same statement-sheet and entered in duplicate. The 25 several parts are especially adapted and designed to facilitate the work of the book-keeper by having a salesman when making a sale enter the charge on the monthly statement-sheet which forms the "original-entry" 30 sheet and by the same entry making a duplicate entry on the duplicate portion of such sheet, which forms the journal or ledger sheet, as well as making an entry at the same time on the bill-sheet. The statement and journal 35 or ledger sheets are formed in one part and are detachable from one another, while the bill-sheet is preferably made up in block or book form with several bill portions arranged to the sheet. The way or bill sheet 40 portion of my present invention is identical with that form of bill-sheet shown in the patent granted to Vaughn August 22, 1903, No. 503,918, and my present invention is an improvement on the said patent. The way or 45 bill sheet disclosed in the Vaughn patent from practical use I have found desirable for many purposes; but it does not fill all the requirements, as a special means for producing the monthly statement is necessary, as is the 50 case with the ordinary forms of way or bill

sheets. This method of keeping accounts has its serious objections in that the several entries made from time to time must be copied from the duplicates of the way or bill sheets, and it is usually done by others than those 55 who originally made out the way or bill sheets. In other words, the handwriting is different from that which appears on the way or bill sheet sent out during the month, thereby allowing for much controversy between 60 the seller, the buyer, and the delivery-clerk as to the proper entries made, &c.

My present invention in its more complete nature also embodies a special form of duplicate statement-sheet whereby when it is separated from the block of way or bill sheets it can be readily located within a suitable file-case, and it is also specially designed to be used with the particular form of way or bill sheets disclosed in the patent to Vaughn, 70 hereinbefore referred to, all of which will be hereinafter fully described, and pointed out in the appended claims, and described in the accompanying drawings, in which—

Figure 1 illustrates my combined bill, statement, and journal or ledger sheets, showing the same arranged in position for use. Fig. 2 is a view of one of the blank way or bill sheets, showing the same lined up for a number of 75 separate accounts of way-bills. Fig. 3 is a 80 similar view of one of the duplicate statement and journal sheets. Fig. 4 is a diagrammatic view on the line 4-4 of Fig. 1.

In the practical application of my invention I provide a series of way or bill sheets 85 bound together in a book or block form, and each of said sheets has ruled spaces and otherwise marked or arranged substantially the same as is shown in the Vaughn patent before referred to. In the present arrangement 90 of the way or bill sheets A, however, the two vertical columns *a a'* at the right of the advertisement or head portion of the bill are utilized for designating the month and date. In the drawings I have shown the sheets A 95 provided with horizontal perforations *a²* to divide the sheet into a number of separate bill-sheet portions, so that the same may be readily detached for the use of the delivery-clerk in a manner hereinafter more fully un- 100

derstood. The bill-sheet A has the usual horizontal lines a^5 and the vertical columns $a^6 a^7$ at the right-hand edge, and the said columns $a^6 a^7$ extend the full length of the sheet from 5 top to bottom, as shown.

- The statement and journal or ledger sheet S consists of a number of leaves, of which s designates the statement-sheet, upon which all "original entries" are made, and s' designates 10 the journal or ledger sheet, which is an exact duplicate of the statement-sheets with the exception that it is made wider than the sheet s to form an additional strip s^9 , provided with perforations by means of which the sheet can 15 be held in a suitable file-case or any suitable filing-cabinet. The statement-sheet s of the duplicate statement and journal or ledger sheet is ruled to provide columns $s^6 s^4$, which correspond in width and location to the columns 20 $a^6 a^4$ of the bill-sheet A, and the said statement-sheet s is also provided with horizontal lines s^5 , which correspond in width and location to the lines a^5 of the bill-sheet A. At the top of the sheet s is provided with the usual heading 25 s^8 , as clearly shown in Figs. 1 to 3 of the drawings. The statement-sheet s is also provided with columns $s^7 s^7$, which correspond to and register with the columns $a^6 a^7$ of the sheet A, as clearly shown in Fig. 1. The journal 30 or ledger sheet s' is likewise provided with horizontal lines and vertical columns which register and are duplicates of the corresponding lines and columns on the statement-sheet s , as clearly shown in Fig. 3. The combined 35 statement and journal or ledger sheet S is formed in practice of a single sheet perforated vertically, as at s^2 , to fold upon said perforated line to form the two sheets $s s'$. (See Fig. 3.)
- 40 C designates a two-leaved carbon-sheet so arranged as to be placed with one portion between the sheets $s s'$ and its other portion between the sheet s' and the pad or book containing the bill-sheets A, as shown diagrammatically in Fig. 4.
- 45 So far as described the manner in which my improved combined bill, statement, and journal or ledger sheet is used is best explained as follows: Assuming the first sale to be made 50 to "Clark," the salesman places the carbon-sheet as indicated in Figs. 1 and 4 and arranges the various sheets as shown in Fig. 1. He then makes his entry directly upon the statement-sheet s until all the entries for that date have 55 been made. This will then make a duplicate copy of the original entry upon the journal-sheet s' and upon the bill-sheet A. After all the required entries have been made on the sheet the carbon C is removed and the combined 60 statement and journal sheet filed away in its proper place in the file-cabinet, the bill-sheets being torn off and handed to the delivery-clerk or driver to be delivered with the goods. Assuming that the entries just 65 referred to have been made up to and in-

cluding May 9, (see Fig. 1 of the drawings,) now suppose that on May 16 Clark buys more goods. The salesman takes out the respective sheet s from the file-case and upon which the previous entries have been made 70 and then places the carbon in position with one part between the sheets $s s'$ and the other part between the sheet s' and the bill-pad and adjusts the sheet S in proper alinement with the bill-sheet on the pad, as shown in Fig. 1. 75 He then makes the required entries for May 16 upon the original statement-sheet, as shown in Fig. 1, and continuing right after the entries which had already been made upon such sheet. In making the entries, say, of May 16 such entries are transferred through 80 the carbon to the sheet in proper order, and also to the bill-sheet A. The only entries, however, appearing on said bill-sheet at this time will be those under date of May 16. 85

From the foregoing it will be seen that the salesman always makes the original entry on the statement-sheet s , of the respective customer and always has the account of said customer in view when making sales. Again, 90 while making original entries the duplicate or journal entry is made upon the sheet s' each simultaneously with the entry made upon the sheet s , and the entry upon the bill-sheet is also simultaneously made with the other 95 entry. The entries made at a time on the statement-sheet s , the journal-sheet s' , and the respective portion of the bill-sheet A are simultaneously made and are all in the same handwriting and precise duplicates of each 100 other. This will avoid much controversy between the customer and the salesman and the delivery-clerk as to the correctness of the three entries—to wit, that on the sheets, that on the sheet s' , and that on the bill portion A. At 105 the end of the month when the statements are to be rendered to the respective customers the bookkeeper merely tears off the sheet s from the sheet s' , strikes the balance, and sends the said sheet s to the customer, which sheet 110 then contains a complete statement of the customer's account, while the sheet s' contains a precise duplicate of all entries made on the sheet s . The sheets s at the end of the month 115 may then be filed away either in book form or any suitable file-case, each sheet s being made with the additional strip s^9 to enable them being bound in book form or in a file-cabinet.

From the foregoing description, taken in connection with the accompanying drawings, 120 it is thought that the complete construction, arrangement, and manner of using my invention will be readily apparent to those skilled in the art to which it appertains.

Having thus described my invention, what 125 I claim, and desire to secure by Letters Patent, is—

1. In a means for entering accounts of the character described, the combination with a bill-sheet having a plurality of bill-heads on 130

one of its sides and horizontal lines and vertical lines and spaces forming columns on that portion of the sheet not covered by the bill-heads; of a supplemental sheet folded upon itself to form two leaves, said leaves each being provided with a bill-head at the top and horizontal and vertically-arranged lines and spaces on each of said leaves registering with each other and similar to the lines and spaces of the bill-sheet, one of said leaves forming the original entry or statement leaf, the other forming the first duplicate or journal leaf, said first leaf being of the same width as that of the ruled spaces of the bill-sheet, and said second leaf having a continuation forming a supplemental strip provided with perforations, and extending beyond the edge of said first leaf, a carbon-sheet detachably fitted between the leaves of the supplemental sheet and the bill-sheet all being arranged substantially as shown and described.

2. In a means for entering accounts of the character described, a bill-sheet having a plurality of bill-heads on one of its sides and provided with a series of horizontal and vertical lines and spaces covering all of its face other

than that part having the bill-heads thereon, a combined statement and journal sheet composed of a single sheet bent upon itself to form two leaves and provided with perforations at 30 said bend, each of said leaves having a bill-head at the upper end similar to the bill-heads on the bill-sheet, each of said leaves having horizontal and vertical lines and spaces adapted to register with the similar lines and spaces 35 on the bill-sheet, the lowermost leaf having an extension running its full length at its outer side and provided with perforations whereby it may be adjusted in a file, a carbon-sheet adapted to be interposed between the leaves 40 of the combined statement and journal sheet and between the said sheet and the bill-sheet, said combined statement and journal sheet being so arranged whereby one continuous account may be kept thereon and so arranged 45 that an original entry made upon the statement-sheet will be duplicated on the journal-sheet substantially as shown and described.
